(57) **CLAIM**

I claim the ornamental design for an exercise apparatus, as shown.

DESCRIPTION

FIG. 1 is a perspective view showing the front, top, and side of the exercise apparatus of the present invention;

FIG. 2 is an elevational view of a first side of the exercise apparatus of the present invention;

FIG. 3 is an elevational view of the rear of the exercise apparatus of the present invention;

FIG. 4 is an elevational view of a second side of the exercise apparatus of the present invention;

FIG. 5 is an elevational view of the front of the exercise apparatus of the present inventions;

FIG. 6 is a plan view of the top of the exercise apparatus of the present invention; and,

FIG. 7 is a plan view of the bottom of the exercise apparatus of the present invention.

The broken line portions of the disclosure are for illustrative purposes only and form no part of the claimed design.
